LEAUME CARLSWERK ACTIEN-GESELLSCHAFT, OF COLOGNE-MULHEIM, GERMANY

ELECTRIC CONDUCTOR FOR SIGNALING PURPOSES

Application filed June 5, 1926, Serial No. 113,922, and in Germany July 9, 1925.

It has long been known that the damping of conductors can be reduced by surrounding the conductor with a magnetic material, thereby increasing its self-inductance. The higher the permeability of the magnetic material with weak fields, the greater is the increase in self-inductance. At the same time however, with the same thickness of material the resistance producing a loss viz, the virtual resistance increases with the permeability, this increase being more rapid than the increase in permeability. As the said resistance unfavourably affects the damping, the higher permeability does not always signify an improvement in the conductance. It has already been pointed out that owing to the relationship above referred to it is necessary to make the thickness of the layer of magnetic material as small as possible, but what exactly is to be understood by the term "as small as possible" has never been defined, that is to say, it has not been specifically stated as to how thick the magnetic layer should be, with any given permeability, in order to obtain the most satisfactory damping.

The present invention indicates how the damping of a conductor having a layer of magnetic material wound round it can be reduced to a minimum with a given permeability of the material of the said layer. In the accompanying drawings, Fig. 1 is a diagram showing the damping as a function of the thickness of the layer of magnetic material and of the permeability, whilst Figures 2 to 6 show the conductor wound in different ways with the layer of magnetic material which is shown in Figure 2 in elevation and in Figures 3-6 in sectional elevation.

Figure 1 clearly shows that in the case of high permeabilities, the proper dimensioning of the thickness of the layer of magnetic material is of considerable importance. In Figure 1 of the accompanying drawings the specific damping β is shown in relationship to the thickness of layer d of the magnetic material, for different permeabilities ($\mu=100, 200, 400, 1000$ and 2000), other conditions being similar. As will be seen, with increasing thickness of layer the damping at first de-

creases, for all permeabilities, and then increases under the influence of the increasing virtual resistance. While at the lower permeabilities, the lowest part of the curve is rather flat with increasing higher permeabilities the same is less and less flat. Thus, the higher the permeability the more important it is to make the layer of the magnetic material of the correct thickness. The lack of knowledge as regards the suitable ratio between permeability and thickness of layer has retarded the employment of materials of higher permeability ($\mu>200$) for signaling conductors. Such materials have not yet been used in connection with telephone cables but only in connection with telegraph cables with which the conditions are simpler in this respect, as the virtual resistance is lower at the low frequencies which are employed in telegraph work.

The present invention takes into consideration all essential factors and indicates for any shape of the magnetic layer the dimensions of the magnetic material corresponding to the minimum total damping for a definite permeability.

In the following discussion, arrangements of the loading material are compared with each other, which have similar geometrical forms, or to be more accurate, the cross sections of which in a plane passing through the axis of the copper conductor, form geometrically similar figures. This comprises single or multiple tape windings, wire windings (with or without air spacings) or any other arrangements. In Figure 2 a copper conductor a is provided with a winding of wire b and similarly in Figure 3, in the latter figure the wire b being comparatively thinner. In both figures the surrounding wiring consists of a single wire without intermediate spacing. In Figure 4 the wiring surrounding the conductor a consists of a wire b with intermediate spacing c . In Figure 5 the conductor a is wound with a single tape wiring b and in Figure 6 with a multiple tape wiring b .

The discussion will hereinafter be limited to one and the same arrangement, the arrangements which are geometrically similar

to each other only differing with respect to the dimensions of the magnetic material used per unit length of the copper conductor. More clearly expressed the arrangements 5 differ from each other by the thickness d of their layers, "d" being understood to represent any dimension taken perpendicularly to the outer surface of the conductor, for instance in the case of multiple tape windings 10 (with or without intermediate air spacings) the diameter or any other dimension increasing proportionately therewith.

The approximation:—

$$15 \quad \beta = \frac{R}{2} \sqrt{\frac{C}{L}} + \frac{\omega t g \delta}{2} \sqrt{LC}$$

holds for the damping β of conductors under certain conditions existing in this case, R being the total resistance, C the capacity, L the 20 self-inductance (all per unit length), and $\omega t g \delta$ the well-known expression for the leakance, i. e. the product of the angular frequency ω and the tangent of the phase angle deviation δ from 90° , which is the phase angle 25 for a perfect dielectricum. With Krarup conductors the total resistance R is equal to the sum of the resistance of the copper R_o , the eddy current resistance ρ_1 , and the hysteresis resistance ρ_2 . Now, as a first approximation, if windings with forms which are 30 geometrically similar (in the sense above described) are compared both L and ρ_2 are proportional to the permeability μ and the thickness of layer d , while ρ_1 is proportional to the square of μ and the third power of d ; thus 35 it can be stated:—

$$L = a \mu d \quad \rho_1 = b \mu^2 d^3 \quad \rho_2 = \mu d$$

and thus:—

$$40 \quad \beta = \sqrt{\frac{C}{2}} \left[\left(\frac{R_o}{\sqrt{a}} \right)^{\frac{1}{2}} d^{-\frac{1}{2}} + \frac{b}{\sqrt{a}} \mu^{\frac{1}{2}} d^{\frac{1}{2}} + \left(\frac{c}{\sqrt{a}} + \omega t g \delta \sqrt{a} \right) \mu^{\frac{1}{2}} d^{\frac{1}{2}} \right]$$

45 in which a, b, c are coefficients of any desired constant value which are eliminated in the final equation.

Differentiating the quotient $\delta \beta / \delta d$ to zero, we obtain the following as conditions for the 50 minimum of β :—

$$\frac{R_o}{\sqrt{a}} \mu^{-\frac{1}{2}} d^{-\frac{3}{2}} = \frac{5b}{\sqrt{a}} \mu^{\frac{1}{2}} d^{\frac{1}{2}} + \left(\frac{c}{\sqrt{a}} \omega t g \delta \sqrt{a} \right) \mu^{\frac{1}{2}} d^{\frac{1}{2}}.$$

This complicated equation is converted 55 into a very much simpler form by substituting again the magnitudes L_1, ρ_1, ρ_2 , whence the following is obtained:—

$$R_o = 5\rho_1 + \rho_2 + \omega L t g \delta.$$

60 Thus with Krarup conductors the minimum damping is obtained if the thickness of layer is such that five times the eddy current resistance plus the hysteresis resistance and plus the product of the angular frequency 65 the angle corresponding to the losses and the

self-inductance are equal to the continuous current resistance. As the above discussion is independent of the precise form of the Krarup surrounding winding, the result holds for any kind of surrounding winding. 70 That it also holds for multiple layers results from the fact that the partial self-inductance and virtual resistance due to the individual layers have additive effects, so that each individual layer can be considered in the same 75 way.

In the case of telephone conductors $\omega L t g \delta$ and ρ_2 are usually small as compared with R_o , so that in this case the thickness of layer 80 of the Krarup material (in the sense above described) must be such that the virtual resistance produced by eddy currents in the ferromagnetic material is approximately equal to a fifth of the continuous current resistance of the conductor. As the eddy current resistance is dependent on the frequency it is necessary to decide for what frequency the rule is to be applied. The distortion must be taken into consideration in this connection. The eddy current resistance is proportional to the square of the frequency, and thus approximately:—

$$\frac{\beta_2 \omega}{\beta \omega} = \frac{R_o + 4\rho_1}{R_o + \rho_1}$$

and if $\rho_1 = R_o / 5$ then

$$\frac{\beta_2 \omega}{\beta \omega} = 1.5.$$

For $\omega = 5000$, which represents in general the mean frequency of the telephone current, this would mean a very great distortion, as the damping will be 1.5 times as great

105

with a value of $\omega = 10000$. On the other hand, an increase in the damping of this magnitude would be tolerable in most cases between $\omega = 7000$ and $\omega = 14000$. It is thus advisable that the rule should be applied for $\omega = 7000$. If still smaller distortion is desired the basic frequency used in the calculation must be still higher.

By inserting a mean value for the loss constants of the magnetic material we obtain from the above rule for the usual sizes of telephone conductors the following approximate conditions for the suitable thickness of the individual layers of the Krarup material in mm.:—

$$125 \quad d = \frac{7}{\sqrt{\frac{1}{\mu^2}}}$$

As an example, the advisable limits for the thickness of layer under normal circumstances, for various permeabilities, are given

130

in the following table on the basis of the relationships reduced according to the present invention:—

Permeability	Thickness of layer
5 300	0.09 to 0.18 mm.
700	0.05 to 0.10
1000	0.04 to 0.08
2000	0.025 to 0.05

What I claim is:—

10 1. A conductor for signaling purposes having layers of ferro-magnetic material wound round it for the purpose of increasing the self-inductance, the said ferro-magnetic material having an initial permeability greater than 200, the thickness of the said layers being such that with the frequencies and current strengths which are employed for the said signaling purposes, the sum of five times the eddy current resistance of the said layers plus the hysteresis resistance and plus the product of the angular frequency, the self-inductance and the tangent of the phase angle deviation from 90° in the insulating material is approximately equal to the continuous current resistance of the said conductor.

20 2. A conductor for telephone communication, having layers of ferro-magnetic material wound round it for the purpose of increasing the self-inductance, the said ferro-magnetic material having an initial permeability greater than 200, the thickness of the said layers being such that, with the current strengths which are employed for the said communication and with an angular frequency of 7000, the virtual resistance is approximately equal to one fifth of the continuous current resistance of the said conductor.

30 3. A conductor for signaling purposes having layers of ferro-magnetic material wound round it for the purpose of increasing the self-inductance, the said ferro-magnetic material having an initial permeability greater than 200, the thickness of each individual layer of the ferro-magnetic material in mm. being for currents with an angular frequency of 7000 approximately equal to

$$50 \quad \frac{7}{\sqrt[3]{\mu^2}}$$

In testimony whereof I have signed my name to this specification.
